UNITED STATES PATENT OFFICE.

MARTIN GRIFFIN QUIGLEY, OF CHARLESTOWN, MASSACHUSETTS.

WATER-LEVEL-INDICATING DEVICE FOR BOILERS.

1,073,518.

Specification of Letters Patent.

Patented Sept. 16, 1913.

Application filed May 24, 1912. Serial No. 699,590.

To all whom it may concern:

Be it known that I, MARTIN G. QUIGLEY, a citizen of the United States of America, and a resident of Charlestown, in the 5 county of Suffolk and State of Massachusetts, have invented certain new and useful Improvements in Water-Level-Indicating Devices for Boilers, of which the following is a specification.

10 This invention relates to pressure gages for steam boilers, and has for its particular object the provision of means within a single casing, of devices for determining the steam pressure within the boilers and also 15 the water level therein.

It has for a further object the provision of means whereby two similar devices are enclosed within a single casing, each of which is adapted to indicate the steam pressure 20 within the boiler so that one is a check upon the other.

25 The invention consists further in the provision of mechanism within said casing whereby the pressure difference between the steam pressure and said pressure plus the water pressure in the boiler is indicated.

30 The invention further consists in certain novel features of construction and arrangement of parts which will be fully understood by reference to the description of the drawings and to the claims hereinafter given.

35 Of the drawings: Figure 1 represents a front elevation of a boiler of any ordinary type showing the invention applied thereto. Fig. 2 represents a front elevation of a gage embodying the features of the present invention. Fig. 3 represents an elevation of the same, showing the cover removed and a 40 portion of the same, including the tube supporting block, broken in section. Fig. 4 represents a horizontal section of the same, the cutting plane being on line 4-4 on Fig. 3, and Fig. 5 represents a horizontal section of 45 the tube supporting block, the cutting plane being on line 5-5 on Fig. 3.

Similar characters designate like parts throughout the several figures of the drawings.

50 In the drawings 10 represents a boiler of any known construction provided with the stack 11.

55 The upper water level is indicated at *a*, the normal thereof at *b*, while the lower water level is indicated at *c*, all on Fig. 1 of

the drawings. From a point above the level *a* and communicating with the steam compartment in the interior of the boiler 10 is a pipe 12 having formed therein a trap 13 operated by a valve 14. The outer end of 60 this pipe 12 communicates with the casing member 15, said casing 15 also communicating by means of a pipe 16 with the interior of the boiler 10 below the water level *c*. The pipe 12 is provided with a valve 17 65 while the pipe 16 is similarly provided with a valve 18. These pipes 12 and 16 are threaded to a block 19 within the casing member 15. The steam pipe 12 communicates directly with the two spring tubes 20 70 and 21 within the casing 15, while through a lateral passage 22 it communicates with a spring tube 23. The free ends of the tubular pipes 21-23 are connected by links 24 and 25 with the segments 26 and 27 as indicated in Fig. 3 of the drawings. The segment 26 meshes with the pinion 28 formed upon the spindle 29 revolubly mounted in the casing 15 and having secured to its outer end the pointer 30. 75

80 Loosely mounted upon the spindle 29 is a sleeve 31 having formed thereon the pinion teeth 32 which mesh with the teeth of the segment 27. As steam is admitted to the tubes 21 and 23 the increased pressure there- 85 in tends to straighten these tubes and cause a movement of the segments 26 and 27 about the pivots 33 and 34 respectively. The sleeve 31 has secured to its outer end a pointer 33. As the segments 26 and 27 90 move about the pivots 33 and 34 the pointers 30 and 33 move in opposite directions about the graduated arcs 35 and 35^x respectively, these arcs being graduated in opposite directions, and if the device is accurately operating the pointers 30 and 33 will 95 always point at the same graduation on each of the graduated arcs. Should these pointers not correspond some adjustment of the device is necessary in order to secure a 100 proper reading and an accurate indication of the pressure within the steam compartment of the boiler. The water pipe 16 connects with the passage 34^x in the block 19 and communicates with the spring tube 35. 105

The free end of this tube 35 is connected by means of a link 36 to a member 37, pivoted at 38, the opposite end of which is connected by a link 39 to the outer end of the spring tube 20. The pivot member 37 is connected 110

by means of a link 39 to the end of an arm 40 forming a part of a gear segment 41 which meshes with the pinion 42 secured to the shaft 43, on the outer end of which is a pointer 44 coacting with the graduated arc 45.

When the conditions are normal in the boiler 10 the pointer 44 will be in the position indicated in Fig. 2 of the drawings relative to the graduated arc 45, but as the water level becomes increased the pointer 44 will move to the right of said figure, and its highest limit of safety will be indicated when the pointer reaches the point marked H, while, when the water level decreases, the lowest point of safety will be indicated when the pointer 44 reaches L. It is obvious that the spring tube 20 is actuated by steam pressure alone, while the tube 35 is actuated by the pressure of the water plus the steam pressure and the combined action of the tubes 20 and 35 under the pressure contained therein will cause the pressure difference between the two to be indicated on the graduated arc 45. When desired to secure the pressure upon the water in the boiler 10 this may be readily determined by closing the valve 17 and permitting the pointer 44 to be moved wholly by means of pressure contained within the spring tube 35. Preferably the arc 45 is graduated in inches so that the exact amount of water in the boiler is at all times indicated by means of the pointer 44.

35 By means of this device the usual glass water gages are entirely dispensed with, and as a consequence breakage of these gages by too much pressure and the consequent flying glass is entirely eliminated.

40 Another advantage of the present device is that as the pipes are much larger than those used in connection with the ordinary glass water gages they are not liable to clog up. In the present construction the expense of constant renewal of glasses and rubber gaskets is obviated, and the time and labor in renewing these glasses and gaskets is saved.

45 The collecting trap valve 14 is operated by hand, and as a consequence the fireman must be attending to his duty at all times or any neglect thereof will be indicated by the gage as the gage will give a false reading when the condition of said trap is such as to prevent the free passage of steam through the pipe 12. This false reading will be indicated by the variation in the readings of the two steam gages.

50 Another advantage is that by the present construction the gage may be brought down into position accessible to the fireman so that it may be readily read, while in some types of boilers where the water gages are used the gage is so high that it is almost impossible for the fireman to read it accu-

rately. The reading of the steam gage, owing to the multiplicity of spring tubes, is more accurate than that of a single gage, and by closing the valve 18 steam may be admitted into the spring tube 20 to operate the pointer 44 so that the reading of this pointer may be compared with that of the pointers 33 and 35 to determine their accuracy. This, of course, would only be necessary when the steam gages materially differed.

55 Much difficulty has been found to exist in the ordinary glass water gages owing to their exploding and resulting in injuries to the engineers and firemen, and as a consequence many engineers on boilers having high pressure have dispensed entirely with the water glass and depend upon the gage cocks alone. Where a water glass is used it sometimes happens that a fireman is called away for a few minutes and he leaves his water at the proper level. Meanwhile the pump starts up faster and when he returns he endeavors to discover the condition of the water level by means of the glass gage cocks, and he loses much time in so doing, this lost time possibly meaning the blowing out of a cylinder head. Again, it sometimes happens that a fireman will come in to start up in the morning and find no water in either glass or bottom cock. Then, unless he is an old hand, he draws the fire and causes a long shutdown until he finds his water and fires up again. By means of the present invention these objections are entirely overcome because the water level can be traced very readily to any desired level both above and below the gage level. By graduating the water level in inches the fireman can at all times note the fluctuations accurately, and finally, by experimenting, determine how to fire his particular boiler and get the best results.

60 It is believed that the operation and many advantages of the invention will be thoroughly understood from the foregoing.

Having thus described my invention, I claim:

1. In a device of the class described, the combination with a casing member of two spring tubes therein; means connecting one of said tubes with the steam compartment of a boiler; means connecting the other tube with said boiler below the water level therein; a graduated scale; a pointer coacting therewith; a spindle therefor; a gear on said spindle; a gear segment meshing therewith; a pivoted member; links connecting the opposite ends thereof with the free ends of said tubes; and a link between said pivoted member and said segment.

2. In a device of the class described, the combination with a casing member; of two spring tubes therein; means for connecting the steam compartment of a boiler with one

of said tubes; means for connecting the other tube with the boiler below the water level therein; a graduated arc; a pointer coacting therewith; a spindle to which said pointer is secured; a pinion on said spindle; a bell crank lever provided with a gear segment meshing with said pinion; a pivoted member; a link between said member and said bell crank lever; and link connections be-

tween the ends of said pivoted member and 10 the free ends of said spring tubes.

Signed by me at 4 Post Office Sq., Boston, Mass., this 21st day of May, 1912.

MARTIN GRIFFIN QUIGLEY,

Witnesses:

WALTER E. LOMBARD,
NATHAN C. LOMBARD.
